PRESSER FOOT FOR SEWING MACHINES

Emil J. Billington, Chicago, Ill., assignor to Union Special Machine Company, Chicago, Ill., a corporation of Illinois

Application July 19, 1941, Serial No. 403,111

12 Claims. (Cl. 112—151)

This invention relates to a presser foot having an attachment or portion which may be readily shifted into operative or inoperative position as the sewing of a seam proceeds and which, when in operative position, serves to assist in turning under or infolding the edge of one of the materials being united and in presenting the same correctly to the stitch forming means. The invention also includes the improved construction and arrangement of the parts of a multi-sectioned presser foot.

A device constructed in accordance with this invention is especially suited for use in the attachment of collars and cuffs to shirts. In the normal operation of attaching a collar, for example, the inner ply of the band of the collar which is to be attached to the shirt is first laid back to back against the inner side or inner ply of the shirt. The outer ply of the band is turned back while the inner ply and stiffener are then secured to the top of the shirt by a line of through-and-through stitching. Upon completion of this operation, the shirt is turned over and the collar is unfolded in preparation for the stitching of the outer ply of the collar band. It is in connection with this operation that the attachment forming part of the present invention comes into play to assist in infolding the outer ply of the collar just in advance of the point at which it is stitched down. Provision is made for readily swinging the attachment into either operative or inoperative position. As the line of stitching swings sharply around the ends of the collar, the attachment is normally disabled.

The improved presser foot is formed in two sections, which are both tilttable, independently, on the supporting shank and one of which is movable bodily on the shank. This enables the presser foot to accommodate itself readily to variations in the thickness of the work at different points, including variations as between the two sides of the presser foot. Such adjustability of the presser foot sections is of particular importance in conjunction with the attachment.

Other features and advantages of the invention will appear from a detailed description of an illustrative form of the same which will now be given in conjunction with the accompanying drawings, in which:

Figure I is a plan view of the improved presser foot and attachment, showing a presser bar in section and showing a portion of the work on which the device is operating, the attachment being in inoperative position;

Figure II is a view similar to Figure I but show-

ing the presser foot in a different position in relation to the work and showing the attachment in operative position;

Figure III is an enlarged front elevation of the presser foot, the attachment being shown in section along the line 3—3 of Figure II and being shown in dotted lines in its inoperative position;

Figure IV is an exploded perspective view of all of the various elements embodied in the presser foot and attachment;

Figure V is a bottom view of the device;

Figure VI is a rear elevation of the device;

Figure VII is a cross section through one of the members of the presser foot, taken along the line 7—7 of Figure IV, and

Figure VIII is a plan view of a collar and shirt assembly at one stage in their attachment.

Turning now to the drawings, the improved presser foot comprises a shank 6 adapted to be secured in any convenient way to a presser bar 7, which, as indicated in Figures I and II, may suitably be hexagonal in cross section at its lower end. This presser bar, it will be understood, may be mounted in any convenient manner in the needle head of the sewing machine and will be urged downwardly toward the work support by an appropriate spring. The shank of the presser foot may be provided at one side with a suitable channel 8 conforming with the shape of the adjacent portion of the presser bar. A slot 9 communicating with the channel is adapted to receive the body of a screw 10 having threaded engagement with the presser bar for clamping the shank thereto.

The lower end of the presser foot shank is bifurcated to provide spaced downward extensions 11 and 12, each having a hole 13 adapted to receive a pin 14 which may be retained in place by friction or by peening over its ends, after the assembly of the various parts. The presser foot may be suitably formed in two sections 15 and 16. Section or member 15 has integrally formed therewith an upwardly extending block or projection 17 having an aperture 18 which receives the pin 14 and thus permits tilting or pivotal movement of the section 15 in relation to the shank. Section or member 16 of the presser foot is preferably provided with a slotted upward extension forming a pair of spaced, integral blocks 19 and 20. Each block has a laterally extending portion 21 adapted to overlie the adjacent edge of the section 15, as best shown in Figure VI. The spacing of the blocks 19 and 20 is sufficient to provide a slot 22 adapted to receive the pin 14 and permit tilting or rocking of the section

16 about the pin and bodily up-and-down movement of this section with respect to the pin. A recess 23 in the top of block 20 is adapted to receive the lower end of a spring 24 whose upper end fits in a small recess in the under surface of the shank 6 between the extensions 11 and 12. It will be apparent that the spring 24 urges the section 16 downwardly against the work and at the same time tends to rock the latter in a direction tending to lift its toe 25, which is preferably curved upwardly to a slight extent. Due to the cooperation of the overhanging portions 21 with the top of the section 15, the latter also tends to follow the movements of section 16. The tilting of the two sections under influence of the spring 24 is limited by engagement of the section 15 with the forward corner 11a of the shank. However, the two sections of the presser foot in passing over the work are capable of independent rocking movement and the section 16 is also capable of bodily, upward movement relative to the pin 14 and hence relative to the section 15. This enables the presser foot to accommodate itself readily to varying thicknesses of material as seams and the like are brought beneath either or both of the sections. The forward end or toe 26 of the section 15 is preferably curved upwardly to a slight extent and the side of this section, adjacent the section 16, is notched, as indicated at 27, to permit the passage of the needle. The side of section 16 toward the section 15 is preferably curved away from the latter slightly, as indicated at 28 in Figure V, and this side is preferably also provided with a concave depression 29, as shown in Figures V and VII, which gradually becomes shallower and then disappears some distance from the end.

In line with the slot 22, between the blocks 19 and 20, or slightly in advance thereof, and at the opposite side of the section 16, there is provided a downwardly and inwardly sloping surface 30. This is adapted to receive the under surface of a correspondingly inclined extension 31 of a fabric guide attachment 32. The latter is secured to the section 16 by means of a screw 33 which passes through an aperture 34 in the extension 31 and is received by a threaded opening 35 perpendicular to the surface 30. The screw 33 preferably has a smooth, annular shoulder portion directly beneath the head, about which the attachment 32 is adapted to swing freely, even when the screw is tightened in place. Extension 31 has its inner end 36 rounded and the surface 37 on the member 16, with which this rounded end cooperates, is similarly curved to permit the attachment to be swung freely from the full-line position of Figure III to the broken-line position in said figure. For this same purpose the corner 30a of the surface 30 is beveled and rounded slightly to avoid interference with the shoulder 31a on the attachment.

To enable the attachment to be swung readily from one position to another, it is preferably provided with a small handle or knob 38 which may be engaged readily by the finger or thumb of the operator. When the attachment is swung to its inoperative position, indicated in broken lines in Figure III, it is preferably retained in such position simply by friction. When shifted into operative position, it will be retained not only by friction but also by gravity, acting as a result of the inclination of the surface 30, and also by the frictional drag of the material which passes over and under a portion of the attachment, in the manner to be later explained. How-

ever, if desired, any suitable detent may be employed for retaining the fabric guide in either operative or inoperative position.

Extending laterally from the attachment 32, 5 adjacent its free end, is a wing portion 39 having an edge 40 extending across the ends of the sections 15 and 16 when the attachment is in operative position. A notch 41 in the edge 40 is in line with a small space 41a provided between 10 the forward ends of the two sections of the presser foot, by the cutting away of a portion of the toe 26 of section 15. On its under surface the wing portion 39 is preferably provided with a rib or ridge 42 at one side of the notch 41, this rib having one edge formed as an extension of the inner side of the section 16. The rib 14 preferably presents a square shoulder at this edge from which the outer end of the wing extends as a blade 39a. However, on the opposite side of the 20 rib there may be provided a smoothly curved fillet 43. Rib 42 and fillet 43 may be formed as an integral part of the attachment or, as indicated in Figure III, these may be welded or otherwise secured to the under surface of the wing. The under surface of the rib is in the plane of the bottom of section 16 when the guide is in operative position. At its forward end the rib is rounded or curved slightly upwardly to facilitate its passage over seams and the like. The main portion of the guide 32 is relieved slightly on its under surface so that actual contact with the work is made only by the rib and blade portions of this member.

We shall now describe in greater detail a typical operation in connection with which the invention may appropriately be used, i. e., the attachment of collars to shirts. Referring to Figure VIII, there is indicated the first step in this operation. The inner plies of a shirt 45 and a collar 46 are first placed back to back with their free edges 47 juxtaposed. The various plies of the shirt and collar are best indicated in Figure III, in which view, however, they are ready for the second operation. Thus, the shirt may comprise an inner ply 48 and across the shoulders an outer ply 49, the inner ply being backed against the inner ply 50 of the band of a collar. A stiffener 51 is provided between the inner ply 50 and the outer ply 52 of the collar. While the 50 collar and shirt are placed back to back, in the manner explained, the inner ply and stiffener of the collar are secured to the plies of the shirt by a through-and-through line of stitching 53. At this time the outer ply 52 of the collar is turned 55 back, as best shown in Figure VIII. If this operation is performed on the machine embodying the improved construction, the attachment 32 will be swung outwardly to its inoperative position.

Next, the shirt will be turned over and the collar folded out into the position indicated in Figures I, II and III. A line of stitching 54 will then be formed around the end of the collar, commencing approximately at the point 54a. As the 65 stitching is formed around the pointed end 55 of the collar band, and the presser foot is close to the button 56, the attachment is left in inoperative position, as shown in Figure I. The inturning of the outer ply is performed by hand at this time. However, when the stitching reaches the point shown in Figure II, the attachment is swung into place by a flip of the finger against the knob 38 so that the end of the blade 39a passes between the outer ply 52 of the collar and the outer ply 49 of the shirt. With but slight assistance from

the operator, the attachment will then turn the outer ply of the collar under and provide a smooth edge to be stitched down to the shirt, in the manner shown. The notch 41, the space 41a and the groove 29 assist at this time in the folding of the edge of the outer ply 52 and in presenting this correctly to the needle operating through the opening 27. At the same time the square shoulder presented by the rib 42 and also the inner side of the section 16, riding against the slight shoulder on the work formed by the stitching 53, will assist further in presenting the work correctly to the needle. A more uniform product is thus formed. Moreover, variations in the thickness of the work at one or both sides of the line of stitching, due to seams and gathers in the yoke of the shirt, will be readily taken care of by the construction and arrangement of the various parts. When the opposite side of the shirt is reached, and the stitching is to be carried around the point and the buttonhole at this end, the attachment is again swung outwardly into inoperative position until the operation is completed.

The invention may also be used to advantage in the attachment of cuffs to shirts and in a number of other operations of related character.

While an illustrative form of the invention has been described in considerable detail, it will be understood that numerous changes may be made in the specific construction and operation of the device without departing from the principles and scope of the invention as defined by the appended claims.

What I claim is:

1. In a device of the class described a presser foot shank, a presser foot member rockably mounted on said shank, said member having a shoulder adapted to assist in infolding the edge of a section of fabric and to maintain said edge at a uniform distance from the line of stitching, and an attachment pivotally carried by said member, said attachment having a portion adapted to be passed between plies of the work being stitched to facilitate the infolding operation or to be freely swung outwardly laterally of the line of stitching and upwardly into inoperative position at will during the formation of a single seam.

2. In a device of the class described a presser foot shank, a presser foot member mounted for free rocking movement on said shank, and an attachment carried by said member on a pivot inclined at an acute angle to the axis of said shank, said attachment having a portion adapted to be passed between plies of the work being stitched and to extend across the line of stitching or to be swung outwardly and upwardly about said pivot into inoperative position at will.

3. In a device of the class described a presser foot shank, a presser foot member mounted for free rocking movement on said shank, and an attachment carried by said member on a pivot inclined at an acute angle to the plane of the work engaging surface of said member, said attachment having a portion adapted to be passed between plies of the work being stitched and to extend across the line of stitching or to be swung outwardly and upwardly about said pivot into inoperative position at will.

4. In a device of the class described a presser bar, a presser foot shank secured to said bar, a foot member mounted for free rocking and bodily movement on said shank, and an attachment carried by said member and movable in a plane at an acute angle to the axis of said presser bar, said attachment having a portion normally ex-

tending between superposed plies of the work being stitched and across the line of stitching and adapted upon movement in said plane to be shifted outwardly and upwardly into inoperative position at will.

5. In a device of the class described a presser bar, a shank secured to said bar, a foot member carried by said shank, said member having a shoulder adapted to assist in infolding the edge 10 of a section of fabric and to maintain said edge at a uniform distance from the line of stitching, and an attachment mounted on said member for movement freely into either operative or inoperative position at will during the formation of 15 a single seam, said attachment having a portion arranged when in operative position to pass between plies of the work in advance of said member and to extend across the line of stitching to facilitate the infolding operation, said portion being above the work and spaced laterally outwardly at one side of said member when in inoperative position.

6. In a device of the class described a presser bar, a shank secured to said bar, a foot member carried by said shank, and an attachment mounted on said member for movement freely in a continuous sweep into either operative or inoperative position at will during the formation of a single seam, said attachment having a portion 25 arranged when in operative position to pass between plies of the work in advance of said member and to extend across the line of stitching, said portion cooperating with the member to infold the edge of the upper ply, said portion being above the work and spaced laterally outwardly at one side of said member when in inoperative position.

7. In a device of the class described a presser bar, a shank secured to said bar, a plurality of independently movable foot members carried by said shank, and an attachment mounted on one of said members for movement freely in a continuous sweep into and out of operative position at will, said attachment having a portion arranged when in operative position to extend across the 40 ends of said foot members and pass between plies of the work in advance of said members, said portion cooperating with the member by which it is carried to facilitate infolding of the edge of the upper ply before it is carried beneath another of 45 said members.

8. In a device of the class described a presser bar, a shank secured to said bar, a plurality of independently movable foot members carried by said shank, and an attachment pivotally mounted on one of said members for movement in a continuous sweep either into or out of operative position at will, the pivot for said attachment being adjacent said presser bar and having its axis inclined at an acute angle thereto, said attachment having a portion arranged when in operative position to pass between plies of the work and extend across the line of stitching in advance of said members and cooperating with the latter to infold the edge of the upper ply.

65 9. In a device of the class described a presser bar, a shank secured to said bar, a plurality of independently movable foot members carried by said shank, each of said members being rockable on said shank and one being movable bodily thereon, and an attachment mounted on said one of said members for movement freely in a continuous sweep either into or out of operative position at will during the formation of a single seam, said attachment having a portion arranged when 70 in operative position to pass between plies of the 75

work and extend across the line of stitching in advance of said members and to cooperate with the latter to infold the edge of the upper ply, said portion being disposed above and to one side of said members when out of operative position.

10. In a device of the class described a presser bar, a shank secured to said bar, a plurality of independently movable foot members carried by said shank, each of said members being rockable on said shank and one being movable bodily thereon, the work engaging surfaces of said members being normally at different elevations, and an attachment mounted on said one of said members for movement into and out of operative position at will, said attachment having a portion disposed in a plane between the normal elevations of said work engaging surfaces and arranged when in operative position to pass between plies of the work in advance of said members and cooperating with the latter to infold the edge of the upper ply.

11. In a device of the class described a presser bar, a shank secured to said bar, said shank having its lower end bifurcated to provide a pair of spaced downwardly extending walls, a pivot pin extending between said walls, a presser foot member having an upward extension mounted for rocking movement on said pin, a second presser

foot member having a slotted projection cooperating with said pin to enable both bodily and rocking movement with respect thereto, said projection engaging said first-mentioned member to limit outward movement of said second member, and a spring urging such outward movement of the second member.

12. In a device of the class described a presser bar, a shank secured to said bar, said shank having its lower end bifurcated to provide a pair of spaced downwardly extending walls, a pivot pin extending between said walls, a presser foot member having an upward extension mounted for rocking movement on said pin, a second presser foot member having a slotted projection cooperating with said pin to enable both bodily and rocking movement with respect thereto, said projection engaging said first-mentioned member to limit outward movement of said second member, a spring urging such outward movement of the second member, and an attachment mounted on said second member having a portion normally extending across the forward end of said members, said attachment being movable on said second member to carry said portion upwardly and outwardly away from said members.

EMIL J. BILLINGTON.
